UNITED STATES PATENT OFFICE.

JEREMIAH L. MAHER, OF WEST SUPERIOR, WISCONSIN.

DESIGN FOR A BELL.

SPECIFICATION forming part of Design No. 21,055, dated September 22, 1891.

Application filed July 31, 1891. Serial No. 401,316. Term of patent 3½ years.

To all whom it may concern:

Be it known that I, JEREMIAH L. MAHER, of West Superior, in the county of Douglas and State of Wisconsin, have invented and produced a new and original Design for a Bell, of which the following is a specification, reference being had to the accompanying drawing, forming part thereof, in which the figure represents in side view the body or shell of a bell, its configuration and ornamentations being in accordance with my new design.

The shell or body *a* of the bell is of hemispherical form and ornamented to represent

a section of the terrestrial globe. Surmounting the body *a* is the miniature figure of a hog, the same being indicated by the letter *b*. The word "Chicago" appears on the said figure; but this forms no part of the design.

I claim—

The design for a bell herein shown and described.

JEREMIAH L. MAHER.
